A bender actuated by a cable jack is disclosed for bending the free end of fence metal top rail that is already supported on at least two supports or posts. The free end of the fence top rail can be bent to the exact amount desired and in the desired place from the last supporting post to the next post in position, and which will at the same time maintain the bent free end in the desired or same plane with the preceding portions of the top rail. Once in position, this bender is self-supporting on the fence, which is particularly desirable when installing high fences from a ladder.

FIG. I

FIG. 2

FIG. 3

FIG.4

FIG. 5

IN SITU FENCE TOP RAIL FREE END BENDER

BACKGROUND OF THE INVENTION

Formerly, the fence installer had to remove the fence top rail several times in providing a proper radius or angle to the fence rail, and doing so makes it difficult, or sometimes impossible, to finally bend the fence top rail at just the desired angle so that the fence may be located exactly as desired. This is even more difficult when a high fence is involved, such as when a ladder must be used to reach its top.

OBJECTS OF THE INVENTION

It is an object of this invention to provide a fence top rail bender that may be supported on the fence and which, when used, will bend the extending free end of the top rail to the exact desired radius without the necessity of removing the top rail from the fence line post loop caps.

A further object of this invention is to provide a comparatively inexpensive fence rail bender that is easy to operate and easy to keep in repair, that is used in cooperation with a conventional cable jack for progressively pulling the extending free end of the top rail to just the desired radius or bend in a single continuous operation while already installed, in part, on at least two supports.

Yet a further object of this invention is to provide a fence rail free end bender that will bend the rail free end just the desired amount while in position and also will maintain the bent end in the desired same horizontal plane with the rail portions already supported on and between the posts.

A further object of this invention is to provide a fence rail end bender that may readily be used on high fences and easily operated from a high ladder because the bender is self-supporting on the fence rail, once it is in position.

Still a further object of this invention is that it may be used in situ on a fence top rail and thus is a desired improvement over prior art pipe benders, such as shown in U.S. Pat. Nos. 630,848; 907,210; 1,247,728; 2,555,723.

BRIEF DESCRIPTION OF THE FIGURES

With the above and other objects in view, this invention consists in the details of construction and combination of parts, as will be more fully understood from the following description, when read in conjunction with the accompanying drawing, in which:

FIG. 1 is a top plan view of the bender of this invention, self-supported in operative position on a fence top.

FIG. 2 is a perspective view of FIG. 1.

FIG. 3 is a detail side view of the hinged ends of the abutment and supporting pipes, on line 3-3 of FIG. 1.

FIG. 4 is a detail side view of abutting end of the abutment pipe and rail on line 4-4 of FIG. 2.

FIG. 5 is a detail top view of the supporting pipe Y-shaped guide and line post on line 5-5 of FIG. 2.

DETAILED DESCRIPTION OF THE INVENTION

There is shown at 10 the in situ fence top rail free end bender of this invention. This bender 10 serves the purpose of bending a fence rail extending free end 12 to the exact desired radius and proper angle to the fence rail 14 already supported in position through line post loop caps 16 and 18 on line posts 20 and 22, and also

maintains the bending free end in a horizontal or desired plane.

This bender 10 includes a longitudinal abutment pipe member 24 having an abutment and surface 26 somewhat complementary to the surface of the fence pipe 14. Extending from the top of pipe 24 at its abutting end 26 is a supporting hook 28 to extend over rail 14 closely adjacent line post 20 and cap 16, this hook being somewhat complementary to the circumference 10 of the fence rail 14. At the other end of abutment pipe 24, an anchor ring 30 extends in a horizontal plane thereto for attaching a hook 54 and chain 48 thereto.

Extending in a substantially vertical plane below abutment pipe 24 is supporting pipe 32 hinged thereto near its non-abutting ring end 30 by a U-shaped bracket 34 and a pivot pin 36 extending through the bracket and the end of supporting pipe 32. The pin 36 may be a bolt and nut if desired. Extending from the opposite end of supporting pipe 32 is a Y-shaped guide 38 adjustably held against the fence line post 20 by an adjustable chain 40 secured to the top of supporting pipe 32 by a half ring 42 welded thereto near the Y-guide end thereof. The top end of chain 40 is adjustably attached by a snap hook 44 secured to a half ring 46 welded to the bottom of abutment pipe 24 but spaced from its abutting end 26.

Secured to the ring 30 on the end of abutment pipe 24 is a chain 48 which ends in a hook 50, the hook end of chain 48 being looped about fence rail 14 and hooked over itself. The length of chain 48 is such that when hooked over rail 14 it extends a short distance as shown from line post 20 toward line post 22. This completes the description of all novel elements of this bender 10.

This bender 10 works in cooperation with a conventional cable jack 52 having a hook 54. A jack cable 56 arranged to be reeled into the jack 52 extends through jack cable guide finger 58 and ends in a cable hook 60, the hook end of cable 56 being looped about the rail free end 12 and hooked over itself at a point distance from the adjacent line post 20 about two or three times the distance of chain hook 50 on rail 14 from the same line post 20 on the opposite side thereof.

OPERATION OF THE INVENTION

The rail free end bender 10 is placed in position with the abutting end 26 of abutment pipe 24 against rail 14 closely adjacent the line post 20 but on the side toward the other rail supporting line post 22. The rail 14 extends through the post loop caps 18 and 16 to the extending free end 12. The supporting pipe 32, hinged thereto by bracket 34 and pivot 36, has its Y-shaped guide 38 rest against line post 20, being adjustably supported in position by the adjustable chain 40. Chain 48 is looped over fence rail 14 between the abutted end of abutment pipe 24 and a short distance toward line post 20, the length of chain 48 limiting such distance. Then, the cable jack 52 is hooked on ring 30 and its cable 56 is drawn out and looped over the rail free end 12 a distance from the line post 20 about two or 3 times the distance of chain hook 50 about fence rail 14 between the two line posts 22 and 20. Then, operating the cable jack 52 by its jack handle 62 will draw in the fence rail free end 12 as much as desired to provide the desired angle to the fence line post 20, meantime maintaining the bent free end 12 in a desired plane, because the abutment pipe 24 is supported in this desired plane by

supporting pipe 32 and its Y-shaped guide against line post 20 and its adjusted chain 40. Then, a line post loop cap is slid over the then extending free end and secured to the next positioned line post in the conventional manner, and the process is repeated as necessary.

ELEMENTS OF THE DRAWING

In the drawing, like numbers refer to like parts, and for the purpose of explication, set forth below are the numbered parts of the improved in situ fence top rail free end bender of this invention.

	Shown in FIGS.
10	Fence top rail extending free end bender
12	Extending free end of top rail
14	Fence top rail between line posts
16	Line post loop cap on post 20 adjacent free end 12
18	Line post loop cap on post 22 remote from free end 12
20	Line post adjacent free end 12
22	Line post remote from free end 12
24	Longitudinal abutment pipe member
26	Abutting end
28	Supporting hook extending from top abutting end 26
30	Anchor ring on non-abutting end of abutment pipe 24
32	Longitudinal supporting pipe
34	U-shaped hinge bracket on anchor ring end of abutment pipe 24
36	Pivot pin through bracket 34 and hinged end of supporting pipe 32
38	Y-shaped guide means on end of 32
40	Adjustable chain between end of pipes 24 and 32
42	Anchor half ring on 32
44	Snap hook for 40
46	Anchor half ring bottom of 24
48	Chain secured on ring 30
50	Hook on chain 48
52	Cable jack
54	Hook on cable jack 52 for mounting it on ring 30
56	Cable of cable jack
58	Cable guide finger on jack 52
60	Hook end of jack cable 56
62	Cable jack operating handle

Although this invention has been described in detail, such description is intended as being illustrative rather than limiting, since the invention may be variously embodied.

Having thus set forth the nature of this invention, what is claimed is:

1. For use in bending the extending free end (12) of a fence top metal rail (14) supported in position on two fence posts (20, 22) and having the free end (12) extending beyond one (20) of said supporting posts; a fence top rail free end bender (10) comprising a longitudinal abutment member (24) having one end surface (26) to be abutted against the surface of the rail (14) between the two supporting posts (20, 22) and closely adjacent that post (20) from which the free end (12) extends, a hook (28) extending from said abutting end (26) of said abutment member (24) to be extended over the top rail (14) in the abutment end (26) supporting position, a longitudinal supporting member (32) for supporting said abutment member (24) in a desired plane, means (34, 36) hingedly securing one

- end of said longitudinal supporting member (32) to said abutment member (24) adjacent its non-abutting end, a post cooperating guide means (38) mounted on the other end of said longitudinal supporting member (32), means supporting said guide means end of said longitudinal supporting member (32) on said longitudinal abutment member adjacent its abutting end (26), a flexible member (48) secured at one end to said non-abutting end of said abutment member (24) and provided at its free end with a hook (50) to be looped about the fence rail (14) between the abutment member (24) abutting area and the remote post (22) and hooked over itself, in cooperation with a cable jack (52) secured to the non-abutting end of said abutment member (24) and at its other end to the extending free end (12) of the top rail (14) a distance from the adjacent post (20) substantially greater than the distance of the looped flexible member hook (50) from the other side of said adjacent post (20) therebetween, whereby pulling operation of said cable jack (52) will pull and bend the free end (12) of said top rail (14) on a radius at its adjacent post (20) in said desired plane.
2. The bender of claim 1, said abutting end surface (26) of said abutment member (24) being somewhat complementary to the fence rail (14) surface.
3. The bender of claim 1, said abutment hook (28) being somewhat complementary to the fence rail (14) surface.
4. The bender of claim 1, said hinge securing means comprising a U-shaped bracket extending over the non-abutting end of said abutment member (24) and pin pivot means (36) extending through said bracket (34) and said hinged end of said longitudinal supporting member (32).
5. The bender of claim 1, said flexible member being a link chain (48).
6. The bender of claim 1, said means supporting said guide means (38) end of said longitudinal supporting member (32) on the abutting end (26) of said longitudinal abutment member (24) comprising a chain (40) secured to said longitudinal abutment member (24) and to said longitudinal supporting member (32).
7. The bender of claim 6, and chain (40) length adjusting means comprising a hook (44) secured to one said longitudinal member (24), said chain (40) being secured to the other said longitudinal member (32).
8. The bender of claim 7, and half ring means (42, 46) welded to each said longitudinal member (24, 32) providing the means for securing said chain to said other longitudinal member (32) and for securing said hook (44) to said one longitudinal member (24), said hook being a snap hook.
9. The bender of claim 8, and a ring (30) secured on the non-abutting end of said abutment member (24) providing anchor means for attaching said flexible member (48) and the cable jack (52) to said non-abutting end of said abutment member 24.
10. The bender of claim 9, said flexible member being a link chain 48, said longitudinal members being pipe members (24, 32).
